(57) **CLAIM**

The ornamental design for a clip for writing instrument, as shown and described.

DESCRIPTION

FIG. 1 is a perspective view of the invention;

FIG. 2 is a back view of the invention;

FIG. 3 is a side view of the invention;

FIG. 4 is a front view of the invention;

FIG. 5 is another side view of the invention, showing the side opposite that shown in FIG. 3;

FIG. 6 is a top view of the invention; and,

FIG. 7 is a bottom view of the invention.

The writing instrument shown in broken lines in the drawings of FIGS. 1-7 is included for the purpose of showing portions that form no part of the claimed design.
